UNITED STATES PATENT OFFICE.

JAMES B. MACDUFF, OF BROOKLYN, NEW YORK.

FLYING-MACHINE.

No. 905,547.

Specification of Letters Patent.

Patented Dec. 1, 1908.

Application filed April 16, 1908. Serial No. 427,502.

To all whom it may concern:

Be it known that I, JAMES B. MACDUFF, a citizen of the United States, residing at Brooklyn, in the county of Kings and State of New York, have invented certain new and useful Improvements in Flying-Machines; and I do declare the following to be a full, clear, and exact description of the invention, such as will enable others skilled in the art to 10 which it appertains to make and use the same.

This invention relates to flying machines and has for its object to produce a flying machine supported, propelled and guided by 15 rotating air propellers.

Another object is to produce a device of this kind which will be convenient and efficient in operation. To accomplish this is provided a plurality of horizontally and 20 vertically disposed cylinders having propeller blades at the mouth thereof whereby a partial vacuum is formed in front of said propeller blades and the air is congested in the air cylinders behind said blades.

Another object is to provide such an arrangement of said horizontally and vertically disposed cylinders that air blasts generated by said cylinders contact each other in such a manner as to momentarily divert 25 them from their direct course of escape from their respective cylinders temporarily retarding their progress thereby still further augmenting the compression and resistance and thus accelerating the movement of the 30 machine.

For these and still other objects which will appear as the description proceeds, the invention consists of certain novel features, arrangements and combinations of parts of 40 which the herein described flying machine is one of many possible embodiments.

While herein the description refers to minute details of the invention, the invention is not limited to these as the details of construction and combination may be greatly varied without departing from the spirit and scope of the invention.

In the annexed drawing forming a part of this specification in which like reference 50 characters refer to like parts throughout the several views and which are for illustrative purposes and therefore not drawn to any particular scale, Figure 1 is a front elevation; Fig. 2 is a top plan view; Fig. 3 is a 55 longitudinal sectional view.

The main features of this invention are

the vertically disposed open ended cylinders 1 and the horizontally disposed cylinders 2. One of each of these is provided on each side of the longitudinal central plane of the machine and they meet each other at right angles as shown. Said cylinders are supported upon a frame 3 having cross braces 4 and are supported by forward wheels 5 and a rear wheel 6, said wheels having spring connection as at 7 with the frame whereby the machine will not be jarred excessively or broken when it descends. About midway of said frame is provided a gasoline engine 8 or other source of power. The shaft 9 of 70 said engine is provided with a forward sprocket wheel 10 and a rear sprocket wheel 11. Clutches 12 and 13 serve to disconnect said sprockets from said shaft. The sprocket 10 is provided with a chain passing over the upper sprocket 31 rotatably mounted upon the forward center shaft 14, suitably supported as at 16 and connected to laterally extending shafts 17 which are in turn geared to horizontally lying shafts 18 80 coaxial with the cylinders 2 and carrying at the forward end a propeller 19.

A sprocket chain connects the sprocket wheel 11 with the sprocket 20 upon the shaft 21 and the forward end of said shaft is connected by means of the clutch 22 with the beveled gears 23 intermeshing with the gears on the rear laterally extending shafts 24 having gears intermeshing with gears on the vertically extending shafts 25 carrying the 90 propellers 26 in the upper part of the cylinders 1.

The rear end of the shaft 21 is provided with a beveled gear 27 intermeshing with the horizontal gear 28 in turn intermeshing with 95 the beveled gear 29 upon the short shaft 30 carrying the rear propeller 31. The short shaft 30 is carried in a bearing support 32 rigidly secured upon the rotatable vertical support 33 carrying the wheel 6. A wheel 34 100 upon said vertical support 33 is adapted to receive a belt or the like 35 connected to a pulley wheel 36 on the shaft of the steering wheel 37 by means of which horizontal direction of said propeller 31 is controlled. A 105 clutch 38 is provided intermediate the ends of the shaft 21. A link and lever 39 and 40 placed in a convenient position enables the operator to operate said clutch.

The operation of the machine is as follows:—The gasoline engine is started as is usual and any of the propellers 19, 26 or 31

may be thrown in gear by means of the clutches 12, 13, 22 and 38, thus causing the machine to move upwardly or downwardly or forwardly as desired. The steering is done by means of the wheel 37 as has been explained.

Having thus described my invention, what I claim as new and desire to secure by U. S. Letters-Patent is:—

- 10 In a machine of the character described, a pair of horizontally projecting cylinders, a pair of vertically projecting cylinders extending at right angles to said horizontally projecting cylinders and having the outlets

thereof arranged adjacent the outlets of the 15 horizontally projecting cylinders, fans journaled in all of said cylinders, a mechanism for operating said fans, the blast from said fans in the vertical cylinders crossing that of the blast from the forwardly projecting cylinders.

In testimony whereof I have hereunto set my hand in presence of two subscribing witnesses.

JAMES B. MACDUFF.
